(57) **CLAIM**

The ornamental design for an electric bug zapping racket, as shown and described.

DESCRIPTION

FIG. 1 is a perspective view of an electric bug zapping racket showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of another state of the electric bug zapping racket thereof;

FIG. 9 is an enlarged view of the selected portion in FIG. 1; and,

FIG. 10 is an enlarged view of the selected portion in FIG. 1.

The broken lines shown in the drawings depict portions of the electric bug zapping racket in which the design is embodied that form no part of the claimed design. The dot-dash broken lines represent the boundaries of the enlarged portions and form no part of the claimed design.
